LINK BELT UNLOADER

Arnold Baker, New Haven, Conn.

Application March 1, 1944, Serial No. 524,576

1 Claim. (Cl. 86—48)

(Granted under the act of March 3, 1883, as
amended April 30, 1928; 370 O. G. 757)

1

The invention described herein may be manufactured and used by or for the Government for governmental purposes without the payment to me of any royalty thereon.

The invention relates to means for unloading cartridges from metallic link belts, and its object is to provide an extremely simple device which may be used as a part of a standard manually operated link loading machine, to the end that no special machine need be constructed, but by the simple expedient of laying, inserting, or applying an element to the standard loader the latter is converted to an unloader of highly efficient function.

As is well understood, ammunition for machine guns is assembled in belts of suitable length which are engaged by the automatic loading mechanism of the gun to feed the same to the chamber and firing mechanism of the gun.

These belts consist of metal cartridge-clasping links separate from each other, but held together by the cartridges inserted therethrough. This form of ammunition is used in .30 caliber and .50 caliber guns, and the .50 caliber ammunition is practically all supplied in belt form. At the manufacturing plants, and in the field, for purposes of inspection, or to supply rounds in small number for single shots or limited practice, instructional and other uses, it is frequently necessary to unload the belts of their cartridges, sometimes in considerable numbers. As considerable force is required to disengage the cartridges from the links (approximately 5 or 12 lbs. pressure on each), it is practically essential when a considerable quantity is to be unloaded, to employ leverage to withdraw the rounds from the links, and to effect this in gangs, to economize time since the extent of such service does not warrant use of automatic or power operated machines. In a standard manual link loader leverage devices are available for the application of the necessary force in the required extent of movement, and it is therefore a paramount object of this invention to present a simple article which by being merely set in place on the usual cartridge-receiving base plate of the loader will cause the loader to function as an extractor, with corresponding advantages in ease and rapidity of work. It is a further important aim to so construct the device that it will be rugged and not liable to damage or deterioration by severe use.

In addition, it is sought to obviate the need for change of structure or operative relations of the parts of the loader, and to eliminate the need for use of tools or fastenings in applying my in-

vention to the loader, but to enable this to be done manually, and with certainty as to the proper positioning of the parts for the desired functions, without requiring special mechanical ability or knowledge on the part of the worker applying and using the invention.

Additional objects, advantages and features of invention reside in the construction, arrangement and combination of parts involved in the embodiment of the invention, as will be readily apparent from the following description and accompanying drawings wherein:

Fig. 1 is a plan view of a link loader with my invention applied.

15 Fig. 2 is a side elevation thereof.

Fig. 3 is a top view of the accessory alone.

Fig. 4 is a fragmentary view similar to Fig. 1 showing a modification of the accessory.

While my invention may be embodied in a special machine for exclusive use as an unloader, it is considered preferable to use it as a part of the conventional loader, so that the latter may be alternatively used as an unloader also; and the structure necessary for the one embodiment 20 will be understood from a disclosure of the other.

The loader customarily consists of a bed plate 10 of rectangular form, across and against one end edge of which a stop 11 is bolted, having upstanding abutments or lugs 12 spaced at intervals corresponding to those of cartridges in the belt.

The bed plate is formed with a number of parallel channels 13 alined with the spaces between the lugs 12 and at right angles to the stop 11, extending from the stop a distance slightly greater than the length of a cartridge (including its bullet).

At the opposite side of the plate 10 from the stop 11 a bail lever 14 is pivoted at the extremity 40 of its arms 22. The bight portion of the bail member constitutes an operating handle 15. A slide 16 is mounted on the top side of the plate 10 having inturned flanges 17 engaging around and under horizontal side flanges 18 at respective sides of the plate extending from the stop 11 to near the opposite side of the base plate.

This slide carries a cross bar or pusher 19 extending entirely across the base plate and having a vertical planiform face 20 parallel to the stop 11. The slide is connected to the bail lever by links 21 at each side pivoted on the inner sides of the base arms 22 of the bail and between respective pairs of ears 23 extended upwardly from the bar 19 near each end of the latter.

55 The distance of the pivots of the links on the

arms 22 from the fulcrum pivots 24 of the bail on the base plate is such that when the lever is lowered to a small angle to the plate, in usual loading operation, the bar 19 is spaced from the stop 11 approximately the length of the cartridge case 25, and when the bail is raised to a maximum, the bar is spaced from the stop more than the length of a complete round.

My invention in the instant embodiment comprises a comb-like frame 26, consisting of a flat rectilinear across bar 27 laid removably over and spaced above and horizontally across the channels 13 and beyond, its rear edge resting against the abutments 12. Set on edge and secured rigidly to the underside of this cross bar here are planiform vertical parallel plates or fingers 28, extending at right angles to the bar, and having a length slightly less than the length of the case of the cartridge. The fingers have a thickness horizontally somewhat less than the spacing between mutually adjacent cases of rounds in a belt of ammunition, and the height of these fingers is about equal to the diameter of the cartridge case. The length, height, and thickness of these fingers may vary considerably without impairing the function of the device. The fingers are spaced at the same intervals as the abutments 12, and consequently rest on the respective rib parts 29 between the channels 13. If desired one or more finger lugs 30 may be formed at the rear side of the crossbar 27 of the comb device 26, as in Fig. 4, to facilitate alinement of the fingers between the channels 13, and prevent lateral movement of the cross bar. The comb frame may be regarded as a continuation of the abutment devices when set in place, and part of a support means including the base plate 10.

In use, a loader as described is set in position on table or other support and my comb frame set thereon as shown. While the comb frame may be fixed on the loader by separable or screw fastenings, it is not necessary. The bail lever is raised to its maximum while a belt of ammunition is laid across the base plate 11 and the comb frame, with the links 31 just beyond the ends of the fingers, the bullets 32 toward the slide, and the cases lying between the fingers 28. The links are then arranged close to the ends of the fingers 28, or may be a distance therefrom. In this way the rounds tend to quickly adjust themselves between the fingers, and it is not essential that the fingers be accurately alined with the ribs 29, although it is desirable that the fingers be within the lateral limits of the base plate.

The belt being positioned, the rounds will lie in, or tend to adjust themselves in, the channels 13, and the lever 14 is then swung toward the stop 11 and downward. This brings the bar 19 against the tips of the bullets pressing the belt toward the comb frame until the fingers engage the links between the cartridges. Thereafter, continued movement of the lever presses the rounds through the links until the neck portions of the cases are moved into the larger clasp

members of the links and the bullets lie free in the smaller clasp members. The bases of the cases move freely under the bar 27 as far as necessary, but the bullets remain loosely in the links. The rounds are thus completely freed and may be gathered and disposed of as desired while the links, loose and detached from each other, are cleared away and the unloading operation repeated on another portion of the belt. Ordinarily, for .50 caliber ammunition, the unloader is proportioned to unload ten rounds at a time, but the number of rounds accommodated may be varied as the service demands.

While the finger plates 28 have been assembled and welded on the cross bar 27, the comb frame may be cast or produced otherwise as found convenient.

The essential loader members cooperating with my comb frame may be regarded as a unitary machine which may be constructed as such if desired, and the specific disclosure here made, while representing the best embodiment of my invention known to me, nevertheless is purely exemplary so that modifications of construction and arrangement, substitution of materials and equivalents mechanical and otherwise may be made without departing from the spirit of the invention as set forth in the appended claim, wherein I claim:

A link belt unloader for use with a link belt loader having a support for the rounds and links, means for urging the rounds rearwardly longitudinally on the support, and abutment means on the support rearwardly of the rounds, comprising a removable crossbar adapted to be positioned on said support against said abutment and having secured to the underside thereof a plurality of planiform vertical parallel plates extending at right angles to said bar and arranged to extend between the rounds with their front ends in position to engage the links and strip them from the rounds when said rounds are moved rearwardly, said crossbar being provided with means adjacent its ends for engaging said support to prevent lateral movement of the crossbar relative thereto and maintain the alignment of the plates between the rounds.

ARNOLD BAKER.
